WALLET OF UNITARY CONSTRUCTION

David B. Houghton, Leslie, Ark.

Application November 22, 1955, Serial No. 548,335

5 Claims. (Cl. 150—38)

This invention generally relates to a wallet and more specifically relates to a wallet constructed of unitary construction and including a built-in secret pocket together with a novel arrangement whereby the entire wallet is formed from a single piece of suitable material having a novel arrangement of elements to permit assembly of the wallet with the elements coacting to form the desired construction.

An object of the present invention is to provide a wallet of unitary construction including a generally rectangular member foldable along a plurality of parallel spaced fold lines for forming a wallet having a secret pocket formed by the panels of the wallet together with a novel key carrying means and change purse.

A further object of the present invention is to provide a wallet construction having a readily removable card carrying case.

Still another object of the present invention is to provide a wallet constructed in such a manner that no stitching, gluing or the like is necessary or used in the construction of the wallet thereby permitting the wallet to be constructed in a relatively thin and compact manner.

Other objects of the present invention will reside in its simplicity of construction, ease of operation, compactness, versatility and its relatively inexpensive manufacturing cost.

These together with other objects and advantages which will become subsequently apparent reside in the details of construction and operation as more fully hereinafter described and claimed, reference being had to the accompanying drawings forming a part hereof, wherein like numerals refer to like parts throughout, and in which:

Figure 1 is a perspective view of the wallet of the present invention;

Figure 2 is a plan view of the wallet in open position;

Figure 3 is a plan view similar to Figure 2 with parts of the wallet being moved to an open position;

Figure 4 is a longitudinal, vertical sectional view taken substantially upon a plane passing along section line 4—4 of Figure 2 illustrating the details of construction of the wallet;

Figure 5 is a transverse, vertical sectional view taken substantially upon a plane passing along section line 5—5 of Figure 2 illustrating further structural details of the wallet;

Figure 6 is a transverse, vertical sectional view taken substantially upon a plane passing along section line 6—6 of Figure 3 illustrating the details of construction of the card carrying case and the fastening means therefor;

Figure 7 is a plan view of the blank of material from which the wallet of the present invention is formed; and

Figure 8 is a plan view of the card carrying panel which is assembled with the wallet of the present invention.

Referring now specifically to the drawings, the numeral 10 generally designates the wallet of the present invention which may be either a type of wallet especially

2

adapted for men's use or for women's use whereby the wallet may be formed of any suitable material or color depending upon the use of the wallet.

Referring now specifically to Figure 7, it will be seen that the numeral 12 generally designates the blank of material from which the wallet 10 of the present invention is constructed.

The blank 12 is generally rectangular in shape and constructed from a unitary piece of material and includes a back panel 14, a front panel 16, a first intermediate panel 18 and a second intermediate panel 20. The back and front panels 14 and 16 are connected along a longitudinal fold line 22 which forms the bottom of the wallet 10 and the first intermediate panel is connected to the back panel by a fold line 24 which forms the top edge of the wallet 10 and the second intermediate panel 20 is connected to the front panel 16 by a fold line 26 which also forms the top edge of the wallet whereby the facing surfaces of the intermediate panels 18 and 20 form the receptacle portion of the wallet for receiving paper money wherein these facing surfaces are both of finished material. The lower edge of the second intermediate panel 20 may be tapered as indicated by the numeral 28 for facilitating the positioning thereof and the lower edge of the first intermediate panel is free from the back panel 14 whereby a secret pocket may be formed between the first intermediate panel 18 and the back panel 14 for positioning paper money or similar articles therein in concealed relation.

The back panel 14 is provided with a tab 30 on one end and an interlocking tab 32 on the other end and the intermediate panel 18 is provided with an interlocking tab 34 on one end thereof remote from the interlocking tab 32 on the back panel 14.

The interlocking tabs 32 and 34 are each provided with double or spaced inwardly extending anchor slits 36 which are inclined inwardly and towards the center of the respective tabs 32 and 34.

The front panel 16 is provided with a pair of transverse slits 38 adjacent each end thereof forming transversely elongated loops 40 adjacent each end thereof for receiving the tabs 32 and 34. The free end portions of the tabs 32 and 34 are inserted under the respective loops 40 with the outermost edge of the outermost slit 36 engaging the inner edge of the loop 40 and the innermost slit 36 engaging the outer edge of the outer slit 38 which forms the loop 40 and the portion of the tabs 32 and 34 between the slits 36 which is designated by the numeral 42 is disposed in underlying relation to the front panel 16 at the ends of the loops 40 thereby forming a double anchor for the interlocking tabs 32 and 34 so that the tabs 32 and 34 will be securely locked to the front panel 16.

The front panel 16 is provided with a pair of smaller transverse slits 44 forming a small key retaining loop 46 adjacent the interlocking loop 40 wherein the loop 46 is disposed in underlying relation to the tab 34 for positioning and partially concealing the key 48 as specifically illustrated in Figure 3.

The front panel 16 is provided with a cut-out area 50 immediately inwardly of the fastening loop 40 wherein the cut-out area underlies the free end of the tab 32 and forms a change purse when the free end of the tab 32 is secured to the front panel 16 by snap fastening means 52 substantially as illustrated in Figure 3.

The free end of the tab 30 on the back panel 14 is provided with one half of a snap fastener 54 and the other half of a snap fastener 56 is provided on the back panel 14 adjacent the tab 32 wherein the tab 30 will bridge the free end of the wallet 10 when in folded condition with the tab 30 retaining the wallet 10 in folded condition with the snap fastener portions 54 and 56 being detachably engaged.

The front panel 16 is provided with a transverse slit 58 adjacent the center thereof and the panel 16 as well as the second intermediate panel is provided with spaced apertures 60 adjacent the transverse slit 58. Also, the interlocking tab 34 on the first intermediate panel 18 is provided with a relatively small slit 62 adjacent its junction line with the intermediate panel 18.

An elongated card enclosing panel 64 is provided with a small projecting lip or tab 66 at one end thereof and openings 68 adjacent the center thereof whereby the panel 64 is inserted through the slit 58 and the tab 66 is inserted through the slit 62 for assembling the panel 64 on the wallet 10. The apertures 68 are disposed in alignment with the apertures 60 for receiving a U-shaped element 70 having the bight portion underlying the second intermediate panel 20 and the legs thereof extending through the panel 20 as well as the panel 16 and the panel 64. The free ends of the legs of the fasteners 70 are interconnected by a spring member 72 having one end thereof detachable under a hook 74 whereby a generally U-shaped card carrying case 76 may be retained therein or removed therefrom as desired. The free end of the lip 76 and the other end of the panel 64 are provided with interconnecting snap fastener portions 78 for detachably retaining the card carrying panel 64 in position as illustrated in Figure 4 which will also hide the key 48 disposed behind the loop 46 substantially as illustrated in Figures 2 and 3.

In practical use of the invention, the wallet 10 is formed from the blank 12 without the use of adhesive, stitching or similar fastening means and forms a compact wallet which may be complete disassembled when desired and the specific construction of the interlocking tabs provides a double anchor for the panels of the wallet and the change purse, key holder, secret pocket and card carrying case all cooperate to form a unitary construction which is compact and easy to use.

The foregoing is considered as illustrative only of the principles of the invention. Further, since numerous modifications and changes will readily occur to those skilled in the art it is not desired to limit the invention to the exact construction and operation shown and described, and accordingly, all suitable modifications and equivalents may be resorted to, falling within the scope of the invention as claimed.

What is claimed as new is as follows:

1. A wallet comprising a back panel, a front panel, a first intermediate panel, and a second intermediate panel, said back and front panel being connected along the lower edges thereof, the first intermediate panel being connected to the top edge of the back panel and disposed against the inner surface thereof; the second intermediate panel being connected to the top edge of the front panel and disposed against the inner surface thereof, an outwardly extending tab on each end of said back panel, an outwardly extending tab on one end of said first intermediate panel, means on said front panel for interlocking engagement with the tab on the first intermediate panel and the tab on the end of the back panel

remote from the tab on the first intermediate panel, said tab on the other end of said back panel adapted to bridge the free ends of the wallet for retaining the wallet in folded relation.

5 2. The combination of claim 1 wherein said interlocking means includes a pair of transverse slits adjacent each end of the front panel forming a pair of loops, each interlocking tab including double anchor slits on each edge with the anchor slits receiving the end edge portions of the loops with the outer edge of the outermost anchor slit engaging the inner edge of the loop and the outer edge of the innermost anchor slit engaging the outer edge of the outermost transverse slit with the portion of the tab between the anchor slits underlying the front panel at the ends of the loop.

10 3. The combination of claim 1 wherein said other tab on the back panel is provided with a portion of a snap fastener, and another portion of a snap fastener projecting from the back panel remote from the other tab for selectively retaining the other tab in encircling relation to the free ends of the wallet when folded.

15 4. The combination of claim 1 wherein said interlocking means includes a pair of transverse slits adjacent each end of the front panel forming a pair of loops, each interlocking tab including double anchor slits on each edge with the anchor slits receiving the end edge portions of the loops with the outer edge of the outermost anchor slit engaging the inner edge of the loop and the outer edge of the innermost anchor slit engaging the outer edge of the outermost transverse slit with the portion of the tab between the anchor slits underlying the front panel at the ends of the loop, said front panel having a small loop adjacent to and underlying the tab on the first intermediate panel for forming a key retaining loop, said front

20 35 panel including a cut-out area underlying the interlocking tab on the back panel for forming a change carrying purse.

25 5. A wallet comprising a back panel, a front panel, a first intermediate panel, and a second intermediate panel, said back and front panel being connected along the lower edges thereof, the first intermediate panel being connected to the top edge of the back panel and disposed against the inner surface thereof, the second intermediate panel being connected to the top edge of the front panel and disposed against the inner surface thereof, an outwardly extending tab on each end of said back panel, slit means on said front panel for interlocking engagement with the tab on one end of the back panel, said tab on the other end of the back panel adapted to bridge the free ends of the wallet releasable positioning against the outer surface of the back panel thus retaining the wallet in folded relation.
